UNITED STATES PATENT OFFICE.

SAMUEL EWART AND JOHN WILLIAM EWART, OF LONDON, AND NORMAN WILLIAM PRANGNELL, OF MARYLEBONE, LONDON, ENGLAND.

VENTILATOR FOR LIGHT-PROJECTORS OR LANTERNS.

1,337,832.

Specification of Letters Patent.

Patented Apr. 20, 1920.

Application filed March 25, 1919. Serial No. 284,967.

To all whom it may concern:

Be it known that we, SAMUEL EWART and JOHN WILLIAM EWART, both subjects of the King of Great Britain, residing at 346, 348, 5 350, Euston road, London, England, and NORMAN WILLIAM PRANGNELL, a subject of the King of Great Britain, residing at 16 Stratford Place, Marylebone, London, England, have invented new and useful Im- 10 provements in Ventilators for Light-Projectors or Lanterns, of which the following is a specification.

This invention relates to ventilators chiefly intended for use in connection with 15 the projectors of electric searchlight equipments, the object of the said invention being to provide a ventilator, which affords a large area of surface for cooling the gases or vapors within the barrel or body of the projector and effects the deposition of the solid constituents thereof and in which an upward current or suction will be produced which will promote the evacuation or ejection 20 of the gases or vapors resulting from the combustion of the incandescent carbons or other source of light and which is light-proof or practically so.

In the accompanying drawings—

Figure 1 is a sectional side elevation of a 30 ventilator constructed according to our invention.

Fig. 2 is a sectional plan; and,

Fig. 3 is a sectional end view of the same.

Figs. 4 and 5 are respectively a side view 35 and a plan illustrating a detail of the invention drawn to a larger scale than Figs. 1, 2 and 3; and,

Fig. 6 is a section on the line 6—6, Fig. 4. The improved ventilator comprises as an es- 40 sential feature several tiers, preferably three, of tubes, the tubes of the said several tiers being respectively indicated by the letters *a*, *b*, and *c*. These tubes are arranged in par- 45 allel planes in a casing *d*, preferably rec- tangular in plan and provided with a flange or saddle *e* designed to rest upon the barrel or body of the projector, which in the drawings is indicated by the letter *f*, the said projector having in it an opening through 50 which the body *d* projects. *e*¹ is a packing of a suitable non-conductor of heat arranged between the saddle *e* and the body *f*.

The tubes *a* in the lower series or tier are of quadrangular section and arranged par-

allel to one another as shown in Fig. 1, and 55 the tubes *b* of the second series or tier have approximately the section of an isosceles triangle, and are arranged parallel to one another and to the tubes *a*, *a*.

The tubes *c*, of the third series or upper 60 tier of tubes are also of approximately the same sectional shape as the tubes *b* and are also parallel one to the other.

The tubes *a* are arranged with spaces *g*, 65 between them to allow of the upward escape of the gases, and the triangular tubes *b*, are staggered with relation to the tubes *a*, spaces *h* being left between the adjacent tubes *b* and the tubes *a*. These spaces *g* and *h* constitute angular or sinuous passages 70 which allow the escape of the gases or vapors but prevent the passage of light rays. At the ends of the casing *d*, where sufficient space is not available for complete triangular tubes, angular flanges or baffles *i* are 75 fixed to form spaces *h* between the outer sides of the two end quadrangular tubes *a*, *a*.

If desired an additional tier or tiers of tubes parallel to the tubes *a* and *b* may be employed. The several tubes which are of 80 sufficient length to project completely through holes in the casing *d* have fixed to them, before their insertion into the casing, bands *j* provided with flanges *j*¹, as clearly indicated in Figs. 4 and 5, and when insert- 85 ing the tubes into the casing, the sides of the latter are sprung or bent outward to a sufficient extent to allow of this, the casing, when the tubes are in place, springing back against the flanges *j*¹, *j*¹ on the respective 90 tubes so that the said flanges serve to prevent any beam of light escaping between the tubes and the edges of the holes in the casing into which the said tubes are inserted.

The ends of the tubes which project out- 95 side the casing are flanged against the said outer face, as indicated at *k* Figs. 4 and 5, the flanges *j*¹ serving to support the casing against inward bulging during the flanging operation.

The tubes are each preferably formed of 100 a single plate bent to the desired shape, the edges of the said plate, except at the end portions, surrounded by the bands *j*, being caused to overlap but being left slightly 105 open, to form gaps, as indicated at *l* in Figs. 4, 5 and 6, so that when the ventilator is being moved rapidly through the air, some of

the air passing through the holes will escape through the gaps l , thereby producing a certain amount of up-draft between the tubes which will tend to promote the evacuation of the gases.

Although no direct light rays can pass between the tubes a, b when arranged as before described, the white deposit from the fumes given off by the electric arc will tend 10 to reflect a certain amount of light, and for this reason the third tier of tubes c , hereinbefore referred to is employed, these tubes as before stated, being advantageously arranged across the casing d in a direction at 15 right angles to the tubes a, b . The tubes c are provided with flanges j^1 near the ends and are secured to the casing d in the same manner as the tubes a, b , they are also provided with longitudinal spaces or gaps l, l 20 through which air can escape. An additional series of tubes parallel to the tubes c, c and staggered with relation thereto may be employed if desired.

The ventilator casing d projects above the 25 level of the tubes c , as shown in Figs. 1 and 3 and in this projecting portion slots or openings m, m are formed through which the air can freely circulate. The casing is closed at the top by a cap or hood n having 30 an external flange o which extends downward so as to cover the slots or openings m , and is of such dimensions as to allow the ingress of air and the egress of the gases. The said cap or hood, by preference, is 35 formed of a single sheet of metal and the lower edge of the flange o is beaded inward, as indicated at q in Fig. 1, so that wet or moisture will not collect upon the said bead.

To prevent the possibility of any light 40 escaping beneath the edges or flanges of the hood and being reflected on to the barrel f , a screen or baffle r is fixed to the casing d below the slots m and within the said hood to intercept such rays. The cap or hood n 45 is preferably held in position by transverse bolts s which pass through the flanges o of the said cover and through the casing d , the said bolts carrying distance pieces t for fix-

ing the position of the cap or hood with relation to the said casing.

To the interior of the body or barrel f , screens u, u are fixed which project down toward the electric arc on either side of the ventilator and serve to collect the fumes and direct them to the said ventilator; or, 55 instead of attaching these screens to the body f , as shown, they may be attached to the lower edge of the ventilator.

Claims:

1. A ventilator for light projectors or 60 lanterns comprising a plurality of parallel tubes which extend across the body or casing of the ventilator so that the ends are directly open to the air, the tubes of one tier being staggered with relation to the tubes 65 of the adjacent tier so as to form angular or sinuous passages which will allow the escape of the gases or vapors but prevent the passage of light rays.

2. In a ventilator of the kind claimed in 70 claim 1, the arrangement wherein the tubes of the lower tier are of quadrangular section while the tubes of the superposed tier are of triangular section.

3. In a ventilator provided with super- 75 posed tiers of tubes as claimed in claim 1, the employment of an additional tier of transverse tubes.

4. A ventilator as claimed in claim 1, hav- 80 ing parallel tubes formed with longitudinal spaces or gaps for the escape of air from the interior thereof.

5. A ventilator of the kind claimed in 85 claim 1, having parallel tubes which are of sufficient length to project completely through the casing and are furnished at their ends with flanged bands which form light-tight joints therewith.

6. In a ventilator of the kind claimed in 90 claim 1, the combination with the casing of a cover or hood arranged to conceal the openings through which the gases or fumes escape.

SAMUEL EWART.
JOHN WILLIAM EWART.
NORMAN WILLIAM PRANGNELL.
